CASING SCRAPER

John R. Baker, Pasadena, Calif., assignor to Baker Oil Tools, Inc., Los Angeles, Calif., a corporation of California

Application September 26, 1955, Serial No. 536,406

10 Claims. (Cl. 166—173)

The present invention relates to scraping devices, and more particularly to scrapers especially useful in the removing of undesired substances or protuberances from the inner wall surfaces of well casing, liners, and similar conduits disposed in well bores.

An object of the present invention is to provide a device for scraping the walls of well conduits, that has a much stronger body on which the scraper blades are mounted, and in which the blades can also be made much stronger without increasing the over-all size of the device.

Another object of the invention is to provide a casing scraper having spring devices for urging the scraper blades outwardly against the casing wall, the scraper possessing fewer parts, being of simpler construction, and easier to assemble and disassemble.

A further object of the invention is to provide a casing scraper embodying improved spring devices for urging expansible scraper blades outwardly against the casing wall, the spring device exerting its force along substantially the entire length of the blade on opposite sides thereof, thereby rendering the scraper blade more stable in its operation upon the casing wall.

The invention possesses many other advantages, and has other objects which may be made more clearly apparent from a consideration of several forms in which it may be embodied. Such forms are shown in the drawings accompanying and forming part of the present specification. These forms will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a side elevation of a casing scraper disposed in a well casing, parts of the tool being shown in section;

Fig. 2 is an enlarged partial longitudinal section taken along the line 2—2 on Fig. 1;

Fig. 3 is a cross-section taken generally along the line 3—3 on Fig. 2;

Fig. 4 is a cross-section taken along the line 4—4 on Fig. 2;

Fig. 5 is a cross-section taken along the line 5—5 on Fig. 2;

Fig. 6 is a fragmentary side elevation of a spring device assembled in the body of the tool;

Fig. 7 is an isometric projection of one of the spring elements for expanding a scraper blade outwardly;

Fig. 8 is a cross-section through a modified form of the invention.

The casing scraper A shown in the drawings is adapted to operate upon the inner wall of a well casing, liner or similar conduit B disposed in the well bore and through which it is movable. The main body 10 of the scraper is a generally elongate tubular member provided with a central fluid passage 11. A threaded pin 12 is formed at the upper end of the body for threaded attachment

2

to the lower end of a string of drill pipe C running to the top of the well bore, through the use of which the tool is moved in the well casing B both longitudinally and rotationally. The lower end of the body may be 5 formed as a threaded box 13 adapted to be threadedly attached to the upper pin 14 of the main body of the lower drill bit D. This latter tool D need not be used unless it is desired to drill out a substantial obstruction extending transversely across the casing bore. Circulating fluid may be pumped down the drill pipe C and entirely through the fluid passage 11 in the main scraper body 10, flowing down through the lower bit passage 15, from which it exits into the annulus E between the casing B and the apparatus A, C, D disposed therein. 10 This circulating fluid flows upwardly through such annulus to flush the cuttings to the top of the well bore.

The casing scraper has a plurality of sets 16, 17 of scraper blades 18 and cooperating elements that are angularly displaced with respect to each other, the cutting surfaces or edges 19 of the blades collectively operating upon the entire circumference of the well casing. As specifically shown in the drawings, two sets of scraper blades 18 and associated elements are disclosed, one set being displaced about 60 degrees with respect to the 20 other set. Since each set is shown as including three scraper blades, and since each blade has an effective arcuate extent of about 70 degrees, it is apparent that each set of blades will scrape a total of 210 degrees of arc around the circumference of the casing B, and both 25 sets will scrape about 420 degrees of arc around the casing. Accordingly, the blades 18 of one set 16 actually overlap the blades 18 of the other set 17 insofar as scraping action is concerned, giving full assurance that the entire surface of the casing wall will be covered upon 30 longitudinal movement of the tool A (non-rotary movement) in the well casing B.

Since both sets of scrapers and associated elements are alike, although angularly displaced, a detailed description of one set will suffice for both.

40 In connection with the upper set 16 of blades 18, the main generally cylindrical scraper body 10 is provided with a circumferential groove 20 of substantial elongate extent. The scraper blades 18 are disposed within this groove 20 and are preferably equi-angularly displaced from one another. Each blade is provided with axially 45 separated helical scraper teeth 19 inclined to the axis of the tool to a substantial extent. The lower surfaces 19a of these teeth may be suitably hardfaced to enhance their useful life. The inner portion of each blade 18 is provided with oppositely and outwardly extending elongate curved wings 21 which provide stops or shoulders 22. These stops or shoulders are cooperable with companion overlapping wings 23 extending outwardly in opposite directions from the main central body portions 24 of an elongate blade retainer or stop member 25. 50 These stop members 25 are equi-angularly displaced from one another within the body grooves 20 and are disposed between the blades 18, alternating therewith, as clearly shown in Figs. 3, 4 and 5.

The inner wings 21 on the blades will engage the outer wings 23 on the blade retainer member 25 so that outward lateral expansion of the blades 18 is limited. Each retainer member 25 has one wing cooperating with the shoulder 22 on one blade, the opposite wing 23 of the same retainer member being cooperable with the shoulder 22 on the next succeeding blade around the circumference of the tool.

60 The segments or stop members 25 are firmly secured to the main body 10 of the tool to form a rigid abutment for the blades 18. As disclosed, each segment has upper and lower end ears 26 from which upper and lower lugs 27 extend in an inward direction. An intermediate lug

28 also extends inwardly from the main body 24 of the retainer, although such intermediate lug may be omitted, if desired. The ears 26 and lugs 27 are provided with holes 29, each of which has an outer counterbore 30, these holes being in alignment with threaded holes 31 formed in the main scraper body 10. Fastening elements 32, such as screws, are inserted through the holes 29 for threaded reception in the body bores 31, the heads 33 of the screws being received within the counterbores 30.

The circumferential grooves 20 formed in the body 10 can be turned readily in a lathe, so that the base 34 of each groove is cylindrical in shape. At the upper and lower sides 35 of the circumferential groove 20, and in the same radial central planes as the blades 18 and retainer members 25, the body is provided with recesses 36, 37 that may be formed with a milling cutter. The end ears 26 of each blade retainer segment extend into an upper recess 36 and a lower recess 36, the upper and lower lugs 27 fitting snugly against the flat bases 38 of these recesses so that there is flat bearing engagement between the parts.

Each blade 18 is urged outwardly of the scraper body 10 by a flexible member in the form of a leaf spring 40. The springs 40 bear against the scraper body 10 and against the scraper blades 18 in a particular manner, as described in detail hereinbelow, urging the blades outwardly to the extent limited by engagement of the blade wings 21 with the overlapping or overhanging wings 23 of the retainer segment 25. To avoid interference between each scraper blade 18 and the intermediate lugs 28 on the retainer member, during the inward or outward movement of the blade, the wings 21 on the blades may be provided with notches 43 of sufficient extent as to clear the intermediate lugs.

As was noted above, the upper and lower sets 16, 17 of blades 18 and cooperable elements 25, 40, etc. are indentical, although angularly displaced from each other. Since the scraping elements or teeth 19 on the blades collectively cover the entire circumference of the casing wall, the casing B can be scraped effectively merely by moving the tool longitudinally in the well casing. The springs 40 urge the blades 18 outwardly with substantial force against the wall of the casing B, assuring removal of any undesired substances from the well casing.

The blades 18 preferably make a sliding fit with the end walls 35 of the groove 20, so that any longitudinal thrust is transmitted directly between the scraper body 10 and the blades 18. In the event the tool is rotated to accomplish the scraping action of the casing wall, the blade retainer members 25 will drive the blades in a rotary direction. However, it is preferred to furnish another driving arrangement, which also serves to guide each blade 18 in its lateral movement inwardly and outwardly of the casing body 10.

This last-mentioned objective is accomplished by providing upper and lower notches or grooves 44, 45 on the ends of each blade preferably in a central plane. Companion recesses 37 are also formed on the upper and lower portions of the body at each end of the body groove 20. These recesses 37 may also be formed by a milling operation that may be identical, if desired, to the recesses 36 in which the retainer ears 26 and lugs 27 are disposed. Upper and lower driving blocks or members 46, 47 are fitted within the recesses 37 and are secured to the body 10 as by use of welding material 48. The upper and lower driving blocks 46, 47 for each blade extend toward each other and fit within the end notches 44, 45 in the blade 18. The fit is preferably a sliding one with the walls of the notches 44, 45 so as to guide each blade in its movement inwardly and outwardly of the main body 10. The outer portions 49 of each driving member 46, 47 are preferably flush with the periphery of the body 10, whereas the inner portions 50 may be enlarged transversely, furnishing a greater surface of contact between such large portions 50 and the wall of the notches 44, 45.

Should it be desired to remove material from the casing wall by a rotary operation, the drill pipe C and main body 10 are rotated, this movement being transmitted directly to the blades 18 through the driving blocks and members 46, 47. The inclination of the blade teeth 19 insures full coverage of the inner surface of the casing wall B.

The spring 40 for urging each blade outwardly is flat when unconfined, being of a leaf type (see Fig. 7). This spring is disposed in a body groove 20 behind each blade 18, being of a width that is greater than the width of a blade and of a length that is substantially the same as the length of each blade. The center line portion 70 of each spring 40 will engage the base 34 of the circumferential groove, whereas the side or marginal portions 71 of each spring will engage the wings 21 of each blade along substantially their entire length.

To prevent the driving members 46, 47 from interfering with the ability of each spring 40 to flex, each spring is provided with upper and lower notches 72 that freely receive the upper and lower driving blocks 46, 47. In addition, each spring is provided with side notches 73 into which the intermediate lugs 28 of the blade retainers 25 can extend, so that such intermediate lugs also are prevented from interfering with the deflection of the leaf spring in being forced inwardly toward the base 34 of the groove by the load on the blade, or in tending to straighten out, or expand outwardly, so as to correspondingly shift the blade 18 laterally outward of the body 10 of the casing scraper. The upper and lower driving blocks 46, 47, as well as the intermediate lugs 28, tend to retain each spring 40 in its appropriate position within the groove 20 and behind its associated blade 18, insuring its proper action upon the blade and upon the base 34 of the circumferentially continuous groove 20.

When unconfined, each leaf spring 40 is in the flat condition disclosed in Fig. 7. In assembling the apparatus, each spring is inserted in the circumferential groove 20, with its upper and lower notches 72 appropriately disposed over the upper and lower driving blocks 46, 47. Each blade is then placed in appropriate position, with the upper and lower blade notches 44, 45 receiving the upper and lower driving blocks, the blade then being depressed by means of a suitable tool downwardly against the force of the leaf spring 40. The central portion 70 of the spring will engage the base 34 of the groove, the wings 21 of each blade engaging the side margins 71 of the spring and bending or deflecting the latter into an outwardly convex form, such as disclosed in Figs. 3, 4 and 5. The blade retainers 25 are then mounted between the blade members 18 and are appropriately fixed to the body 10 by the upper and lower screws 32. The intermediate lugs 28 in the blade retainers will pass through the side notches 73 in the springs 40, to avoid interference with the ability of the spring margins 71 to move inwardly and outwardly. Once the screws 32 have all been tightened, the tool (not shown) that has been restraining the blades can be removed and each leaf spring 40 will then tend to straighten out, the side margins 71 urging the blades 18 outwardly to the extent determined by engagement of the side wings 21 with the retainer wings 23.

When the tool A is inserted in the well casing B, since the inside diameter of the casing is usually somewhat less than the unrestrained diameter across the blades 18 with the tool out of the hole, the engagement between the blades and the inner wall of the casing will move the blades inwardly to a slight extent against the force exerted by the springs 40. That is to say, the blade wings 21 will move inwardly out of contact with the retainer wings 23. During the downward movement of the apparatus in the well casing, the blade teeth 19 will collectively scrape the entire circumference of the casing. If at any time it is desired to effect a scraping action by

rotating the drill pipe C and the scraper A itself, the inclination of the helical teeth 19 will insure the performance of the appropriate scraping action during rotation of the blades around and along the inner wall of the casing. During the entire operation of the tool, whether it is moved merely longitudinally or rotationally only, or with a combination of such movements, the springs 40 will be constantly urging the blades 18 outwardly, to insure the exertion of an adequate scraping force of the blade teeth 19 against the wall of the well casing.

By virtue of the use of the leaf springs 40 behind each casing, it is possible to make each blade 18 much thicker than heretofore without increasing the over-all diameter of the tool measured to the edges of the scraper teeth 19. Thus, each blade will be much stronger. In addition, the leaf springs 40 make it possible to maintain the diameter of the base 34 of the circumferentially continuous groove, the base of this groove being uninterrupted so as to insure that it possesses a full annular cross-section, such as disclosed in Figs. 3, 4 and 5. The base 34 of the groove can be made without any interruptions in its surface, such as radial holes and the like (not shown), which would reduce the cross-sectional area in the region of such holes and which would also provide points at which fatigue failures could occur. Actual experience has shown that absence of any holes or depressions in the base 34 of the grooves 20 greatly increases the strength of the body 10 and guards against the body twisting off, or otherwise failing in the region of the grooves 20. Where holes 31 are provided in the body, as for the screws 32, the cross-sectional area of the body is much greater, since such holes are disposed longitudinally to one side of the circumferentially continuous groove 20.

It is to be noted that the side margins 71 of the leaf springs are always tending to move out because of the spring characteristics of the spring elements, and that such margins engage the wings 21 along substantially their entire length. Thus, the spring force is exerted in an outward direction along two widely spaced lines of contact with each blade, urging the blade outwardly without any tendency for its tilting within the circumferential groove 20. The blade 18 moves inwardly and outwardly to substantially the same extent along its entire length. The use of the single spring 40 also minimizes the radial space that is required between the inner surface of the blade and the base 34 of the groove, permitting blades of much greater radial thickness to be employed. In addition, assembly of the tool is much simpler than in devices heretofore used, which normally included a plurality of radial helical compression springs disposed at separated points longitudinally along each blade.

The inventor claims:

1. In a casing scraper: a main body attachable to a drill string and having a groove therein; a scraper blade in said groove shiftable laterally therein and adapted to extend outwardly of said body, said blade having side margins; and at least one leaf spring in said groove substantially coextensive in length with said blade, said spring having a central portion engaging the base of said groove and side margins engaging the side margins of said blade, said central portion being free from engagement with said blade and said side margins of said spring being free from engagement with said base of said groove, whereby said blade is urged outwardly of said body; and means for limiting lateral outward movement of said blade in said groove.

2. In a casing scraper: a main body attachable to a drill string, said body having an external groove therein around its entire circumference, said groove having a base of substantially circular cross-section; circumferentially spaced scraper blades in said groove shiftable laterally therein and adapted to extend outwardly of said body, each of said blades having side margins; leaf springs in said groove behind said blades substantially coextensive in

length therewith, each spring having a central portion engaging said base and side margins engaging the side margins of a blade, said central portion being free from engagement with said blade and said side margins of each spring being free from engagement with said base of said groove, whereby each blade is urged outwardly of said body; and means for limiting lateral outward movement of said blades in said groove.

3. In a casing scraper: a main body attachable to a drill string, said body having an external groove therein around its entire circumference, said groove having a base of substantially circular cross-section; circumferentially spaced scraper blades in said groove shiftable laterally therein and adapted to extend outwardly of said body, each of said blades having side margins; means providing a slidable connection between said body and each of said blades; leaf springs in said groove behind said blades substantially co-extensive in length therewith and slidable along said slidable connections; said springs having central portions engaging said base and side margins engaging the side margins of said blades, said central portions being free from engagement with said blades and said side margins being free from engagement with said base of said groove, whereby said blades are urged outwardly of said body; and means for limiting lateral outward movement of said blades in said groove.

4. In a casing scraper: a main body attachable to a drill string, said body having an external groove therein around its entire circumference; circumferentially spaced scraper blades in said groove shiftable laterally therein and adapted to extend outwardly of said body, each blade having scraping portions and also side wings extending outwardly in opposite directions beyond the scraping portions; a leaf spring behind each blade substantially coextensive in length with said blade, said spring having its central portion engaging the base of said groove and its side margins engaging said wings, said central portion being free from engagement with said blade and said side margins of said spring being free from engagement with said base of said groove, whereby said blade is urged outwardly of said body; and blade retainer members in said groove between said blades, each of said retainer members overlapping the side wings of the blades on opposite sides of the retainer member for limiting the outward movement of said blades.

5. In a casing scraper: a main body attachable to a drill string, said body having an external groove therein around its entire circumference; circumferentially spaced scraper blades in said groove shiftable laterally therein and adapted to extend outwardly of said body, each blade having scraping portions and also side wings extending outwardly in opposite directions beyond the scraping portions; at least one leaf spring behind each blade, said spring having a central portion engaging the base of said groove and side margins engaging said wings, said central portion being free from engagement with said blade and said side margins of said spring being free from engagement with said base of said groove, whereby said blade is urged outwardly of said body; and blade retainer members in said groove between said blades, each of said retainer members overlapping the side wings of the blades on opposite sides of the retainer member for limiting the outward movement of said blades; each spring having notches in its side margins receiving said retainer members.

6. In a casing scraper: a main body attachable to a drill string, said body having an external groove therein; a scraper blade in said groove shiftable laterally therein and adapted to extend outwardly of said body; said blade having an end groove; a driving member secured to said body and slidably received in said end groove to guide said blade for movement laterally of said body; and a leaf spring in said groove having a first portion engageable with said blade and a second portion engageable with

the base of said groove, said second portion being free from engagement with said blade and said first portion being free from engagement with said base of said groove, whereby said blade is urged outwardly of said body, said spring having an end notch receiving said driving member; and means for limiting outward movement of said blade in said external groove.

7. In a casing scraper: a main body attachable to a drill string, said body having an external groove therein; a scraper blade in said groove slidably laterally therein and adapted to extend outwardly of said body, said blade having upper and lower substantially central end grooves therein extending inwardly toward each other from the upper and lower ends of said blade; driving members secured to said body and slidably received in said end grooves to guide said blade for movement laterally of said body; and a leaf spring in said groove having a first portion engageable with said blade and a second portion engageable with the base of said groove, said second portion being free from engagement with said blade and said first portion being free from engagement with said base of said groove, whereby said blade is urged outwardly of said body, said spring having upper and lower end notches receiving said driving members; and means for limiting lateral outward movement of said blade in said external groove.

8. In a casing scraper: a main body attachable to a drill string, said body having an external groove therein; a scraper blade in said groove shiftable laterally therein and adapted to extend outwardly of said body, said blade having side margins and upper and lower substantially central end grooves therein extending inwardly toward each other from the upper and lower ends of said blade; driving members secured to said body and slidably received in said end grooves to guide said blade for movement laterally of said body; and a leaf spring in said groove having a central portion engaging the base of said body groove and its side margins engaging the side margins of said blade, said central portion being free from engagement with said blade and said side margins of said spring being free from engagement with said base of said groove, whereby said blade is urged outwardly of said body, said spring having upper and lower end notches receiving said driving members; and means for limiting lateral outward movement of said blade in said external groove.

9. In a casing scraper: a main body attachable to a drill string, said body having an external groove therein around its entire circumference; circumferentially spaced scraper blades in said groove shiftable laterally therein and adapted to extend outwardly of said body, each blade having scraping portions and also side wings therein extending outwardly in opposite directions beyond the

scraping portions; each blade having upper and lower substantially central end grooves therein extending inwardly toward each other from the upper and lower ends of said blades; driving members secured to said body and slidably received in said end grooves to guide said blades for movement laterally of said body; leaf springs in said body groove behind said blades, each spring having a central portion engaging the base of said body groove and side margins engaging said wings, said central portion being free from engagement with said blade and said side margins of each spring being free from engagement with said base of said groove, whereby each blade is urged outwardly of said body; each of said springs having upper and lower end notches receiving said driving members; and blade retainer members in said groove between said blades, said retainer members overlapping the side wings of the blades on opposite sides of the retainer member for limiting the outward movement of said blades.

10. In a casing scraper: a main body attachable to a drill string, said body having an external groove therein around its entire circumference; circumferentially spaced scraper blades in said groove shiftable laterally therein and adapted to extend outwardly of said body, each blade having scraping portions and also side wings therein extending outwardly in opposite directions beyond the scraping portions; each blade having upper and lower substantially central end grooves therein extending inwardly toward each other from the upper and lower ends of said blades; driving members secured to said body and slidably received in said end grooves to guide said blades for movement laterally of said body; leaf springs in said body groove behind said blades, each spring having a central portion engaging the base of said body groove and having side margins engaging said wings, said central portion being free from engagement with said blade and said side margins of each spring being free from engagement with said base of said groove, whereby each blade is urged outwardly of said body; each of said springs having upper and lower end notches receiving said driving members; blade retainer members in said groove between said blades, said retainer members overlapping the side wings of the blades on opposite sides of each retainer member for limiting outward movement of said blades; each spring having notches in its side margins receiving said retainer members.
